Application May 26, 1938, Serial No. 210,192

5 Claims. (Cl. 196—13)

This invention relates to methods of separating constituents of mineral oils, and more particularly to the use of selective solvents in counterflow systems wherein the solutions are divided into separate layers which flow in opposite directions.

Prior to this invention, the usual object has been to most effectively separate the undesirable constituents from the oil charge in an economical manner, while providing convenient control of the numerous successive conditions which occur in the counterflowing streams. This old object has led to many different variations of the true counterflow system.

To control the successive operations, various combinations of batch and counterflow systems have been proposed. To provide for controlled continuous operation, a combination of mechanical mixers and a series of settling chambers alternating with the mixers, have been associated with separately regulated auxiliary extracting apparatus, the object of such combinations being to most effectively utilize the solvent and at the same time control the successive steps of the procedure. The old apparatus of this kind is complex and quite expensive. It provides for separate control at several stages of the continuous operation, but so far as we are aware, it has failed to most effectively accomplish the desired results.

The effects of temperature changes are fairly well understood, and the old complex systems herein referred to include different kinds of equipment to be operated at different temperatures. However, these prior disclosures lack the desired simplicity and do not set forth a method of obtaining the maximum efficiency from the solvent.

A true counterflow system, wherein the oppositely flowing layers contact with each other has been regarded as an uncertain method, lacking any positive control at the successive stages, although it has the advantage of simplicity not found in the previous use of mechanical mixers alternating with settling chambers. Heretofore, the use of various different kinds of expensive devices and apparatus has been regarded as essential to provide the desired control.

One of the objects of the present invention is to most effectively accomplish all of the desired results in a simple counterflow system, lacking the various different types of separately regulated mixers, settlers, etc., heretofore employed to control the procedure.

A separate and distinct object is to provide

a series of different zones which result in a substantial improvement, and which may be advantageously employed in any of the various types of counterflow systems, including the simplest type wherein the counterflowing layers are in direct contact with each other, as well as the complex systems, involving the use of separate mixing and settling chambers.

More specifically stated, an object is to produce a system including artificially cooled saturating and precipitating zones near opposite ends of the system, with relatively hot scrubbing and refluxing zones between said cooled saturating and precipitating zones. In the preferred form of the invention, the several zones are in free communication with each other and so arranged that the raffinate is discharged from the cooled precipitating zone at one end of the system, while the extract passes from the cooled saturating zone near the opposite end.

Despite the old objections to lack of control in a true counterflow system, and the previous failures in attempts to accomplish the optimum results in complex combinations of different kinds of apparatus, we will hereinafter set forth details showing just how to produce an extract approximately saturated with the lowest grade constituents, while discharging a raffinate containing very little if any excess solvent, and free of other undesirable constituents.

Specific examples will show how the series of zones may be employed to economically accomplish all of these results in a simple counterflow system. In view of this disclosure, it will be apparent that a system of this kind can be very easily regulated to economically produce the highest grade of raffinate and the most degraded extract, or any desired intermediate grades with a corresponding degree of economy. The cooperative functions in the several zones may be determined by simple preliminary adjustments and thereafter maintain without further attention aside from the routine observation of temperatures, etc.

With the foregoing and other objects in view, the invention comprises the novel method hereinafter more specifically described and shown in the accompanying drawings, which illustrate one form of the invention. However, it is to be understood that the invention comprehends changes, variations and modifications within the scope of the claims hereunto appended.

Fig. 1 is a side view of an extracting column embodying features of this invention.

Fig. 2 is a vertical section of the column shown in Fig. 1.

Fig. 3 is an enlarged diagrammatical view, with arrows indicating the counterflowing streams contacting with each other and moving in intersecting paths while flowing from one elevation to another.

Fig. 4 is a section on the line 4—4 in Fig. 3, with arrows indicating the radial counterflow which occurs between the intersecting paths.

Fig. 5 is an enlarged section illustrating zones near the upper portion of the extracting column.

Fig. 6 is a view similar to Fig. 3 illustrating another type of counterflow.

Fig. 7 is a diagrammatical view pointing out conditions which may be maintained in the several zones.

To illustrate a simple system embodying the several features of the invention, we have shown a counterflow system comprising a single vertical column wherein all of the successive operations are performed, and without in any way limiting the patent to this specific example, the details appearing in the drawings will be described as follows:

1 designates a vertical extracting column having an inlet pipe 2 near the top for the continuous admission of a stream of selective solvent, and an inlet pipe 3 near the bottom for the admission of a continuous stream of oil to be acted upon by the solvent. The degraded extract may be continuously discharged through a pipe 4 leading from the lower portion of the column, while the raffinate is continuously discharged through a pipe 5 leading from the upper portion of the column.

The system herein shown is provided with a series of successive zones wherein varying conditions are deliberately maintained, so as to provide for very effective action at each of the numerous stages of the extracting operation. These zones may be located one above the other as shown in the drawings, or arranged in any other suitable manner. Before describing the various conditions, we will briefly state that the zones herein shown include a precipitating zone at the top of the column, a settling zone below the precipitating zone, a solvent zone below said settling zone, a scrubbing zone below said solvent zone, a refluxing zone below the scrubbing zone, a saturating zone below said refluxing zone, and a saturated releasing zone below said saturating zone.

To divide the solutions into numerous counterflowing layers contacting with each other, the interior of the apparatus may include a series of alternating baffle plates 6 and 7, as shown in Figures 2, 3 and 4. Each baffle 6 has a peripheral edge separated from the inner face of the column. Each baffle 7 has a peripheral edge suitably united with the inner face of the column, and a central opening 8 through which the counterflowing solutions of oil and solvent rise and fall in passing from one of the baffle plates to another.

The paraffinic constituents of the oil charge gradually advance toward the top of the extracting column, while the naphthenic constituents are gradually dissolved in the solvent to produce heavier solutions which flow toward the bottom of said column.

By referring to Figures 3 and 4 it will be understood that the solutions of oil and solvent are divided into numerous thin layers of different spe-

cific gravities contacting with each other. These contacting layers move radially in opposite directions, and at gradually changing speeds, toward and away from the central portion of the column. The highest speed is attained near the central portion of the column where all of the liquid must pass through a relatively small opening 8, while the lowest speed is near the periphery where approximately the same volume of liquid flows through a much larger opening between the periphery of a baffle plate 6 and the inner face of the column.

Mixing zones are formed at the central openings 8 where the oppositely moving layers travel 15 in intersecting paths from one plane to another at a relatively high speed. The resultant mixtures are permitted to settle and stratify at lower speeds around the central mixing zone, the speed of each layer being gradually increased as it moves toward the central mixing zone and gradually decreased as it moves away from said mixing zone. The oppositely moving layers also travel through intersecting paths in the zones of lowest speed around the peripheries of the 20 baffle plates 6, so as to provide secondary mixing zones alternating with the primary mixing zones at the central portion of the column.

The solvent is thus combined with oil that enters at the lower portion of the column to provide 25 numerous relatively thin flat horizontal layers distributed in such manner that the natural counterflow is frequently interrupted by mixing at relatively high speeds and settling at lower speeds.

If desired, the baffle plates may be arranged 30 as shown in Fig. 6, wherein the plates 9 are duplicates of each other. One edge of each plate 9 is separated from a wall of the chamber 10, and these plates are staggered to provide a tortuous passageway for the counterflowing solutions.

However, advantages are gained by arranging the baffle plates as shown in Fig. 2. Attention 35 is directed to the varying spaces between the baffle plates 6 and 7 in this view. The adjacent plates are comparatively far apart near the bottom of the column, and substantially closer to each other near the top of the column, the distance between said plates being progressively decreased toward the top of the column. This arrangement progressively decreases the thicknesses of the liquid streams passing from naphthenic phases in the lower portion of the column to more paraffinic phases at higher elevations. 40 The lowest velocities will occur in the thickest layers, and the highest velocities in the thinnest layers, so the arrangement just referred to will result in a progressive increase in the velocity of the rising streams, and a corresponding decrease in the velocity of the descending streams. Consequently, the most drastic treatment will occur 45 in the scrubbing zone where the extremely thin counterflowing layers are moving at the highest velocity, and substantially different conditions are produced in each of the other zones.

Such conditions are deliberately varied to selectively produce different treatments in the several zones, the object being to provide for a high degree of efficiency at each of the numerous stages.

Aside from the velocities and the thicknesses of the counterflowing layers, the effect of the treatment at any given point will depend partly upon the temperature at that point. As an illustration of suitable temperature regulating

devices, we have shown coolers 11 in the precipitating zone, heaters 12 at the scrubbing zone, coolers 13 in the refluxing zone, a cooler 14 at the top of the saturating zone, and coolers 15 in the saturated releasing zone. As an aid in describing one form of the invention, and without in any way limiting the invention to specific temperature conditions, we have indicated a series of temperature variations in Fig. 7. Using these specific temperatures merely for convenience in explaining conditions which may be established and maintained in the different zones, we will briefly refer to each zone, as follows:

The saturating zone

The oil to be extracted may be introduced near the bottom of the saturating zone at a temperature of 60° F. In this zone, the baffles 6 and 7 are spaced apart to provide relatively low velocities in the counterflowing layers. The descending solvent streams, or layers, contact with the rising mass of fresh oil. Assuming that the object is to saturate the outgoing solution with the most degraded naphthenic components at a temperature of 60° F., the saturating zone may be maintained at about 60° F. The low velocity and low temperature are prolonged, and the most soluble (naphthenic) components of the incoming oil are very readily dissolved in the descending solution, while the lighter, more paraffinic portions rise into the less saturated zone.

A study of the conditions in this saturating zone will show that the most degraded naphthenes of the incoming oil are quickly dissolved by the descending solvent, and as the saturation progresses, the less degraded compounds are thrown out of the degraded solution, and transferred to the more paraffinic rising streams. Deliberate saturation of the descending solvent with the most degraded portions of the oil is an important function. It provides for recovery of approximately all of the desired paraffinic compounds in the original oil.

However, it is to be understood that there is no exact line of demarcation between one zone and another, and even when the descending solvent is perfectly saturated with all of the most degraded components of the original oil, the saturated solution may contain entrained paraffinic particles having substantial value. Therefore, advantages are gained by transferring the saturated, or approximately saturated, solution to another zone which will be briefly described as follows:

The saturated releasing zone

The solvent, approximately saturated with the most degraded components of the oil, descends from the saturating zone to the cool saturated releasing zone. The velocity in the last mentioned zone is extremely low, a large body of the approximately saturated solution being maintained between the bottom of the saturating zone and the outlet for degraded extract. These conditions are most favorable to complete saturation, and they positively provide for release of entrained paraffinic compounds, which slowly rise to the surface of the saturated releasing zone, and enter into the rising paraffinic stream. Paraffining material is thus recovered as part of the valuable paraffinic oil, instead of being carried away in the degraded extract.

The refluxing zone

After the most soluble (degraded) portions

of the incoming oil are transferred to the descending solvent in the saturating zone, the less soluble (more paraffinic) portions rise into the bottom of the refluxing zone. At this stage, 5 more drastic treatment is required to produce the desired separation. The temperatures of the rising stream may be progressively increased in the refluxing zone, and the velocities of said rising stream may be increased as suggested by 10 the baffle arrangement in Fig. 2. Opposite conditions appear in the descending solvent stream, wherein the temperatures and velocities are decreased toward the bottom of the refluxing zone.

This combination of conditions establishes an 15 internal reflux wherein semi-naphthenic portions of the descending stream are transferred to the rising paraffinic stream. The descending naphthenic stream progresses through more saturated conditions at gradually decreasing temperatures, 20 so the least soluble portions of the descending naphthenic stream are positively discharged to the rising paraffinic stream. The free interchange of higher and lower grade naphthenes transmits the intermediate grades to the rising stream, while the descending stream becomes 25 more saturated with the lower grade.

In this refluxing zone there is a dispersion of 30 charging stock in a semi-saturated solution of naphthenic compounds, as distinguished from a true solution. There is a concentration of naphthenic oil and an interchange which sifts out the higher grade naphthenes and permits them to rise in the column, while the most degraded portions are retained in or transferred to the 35 descending stream. The cool incoming oil is not immediately dissolved. The most soluble portions are quickly dissolved in the saturating zone, but a substantial portion of the semi-paraffinic solution then rises in globules to the refluxing zone, which immediately starts the recycle.

The interchange in this refluxing zone can be 40 very effectively obtained by progressively increasing the temperatures and velocities of the 45 rising stream, while decreasing the temperatures and velocities of the descending stream, at the same time frequently mixing and settling the counterflowing streams. However, the invention is not limited to this specific combination 50 of details in the refluxing zone.

The scrubbing zone

High temperature and relatively high velocity, 55 with frequent mixing and settling of the counterflowing layers, or any one of these conditions, will tend to improve the paraffinic solution rising from the top of the refluxing zone. Such conditions appear in the scrubbing zone where the relatively thin rising paraffinic stream contacts with approximately all of the fresh incoming 60 solvent. The optimum high temperature may be prolonged in this drastic scrubbing zone to provide time for the solvent to blend with the oil and dissolve the comparatively insoluble intermediate naphthenic components, which enter into the descending solvent stream.

The solvent zone

The fresh solvent enters near the top of the scrubbing zone, and a body of the solvent may 70 be permitted to accumulate in the higher solvent zone. In the specific example herein considered, the selective solvent is relatively heavy, and it selects the heavy naphthenic components of an oil. The body of solvent in the solvent zone may 75 be at a relatively high temperature conforming

approximately to the temperature in the scrubbing zone. Under these conditions, the light solution passing from the top of the scrubbing zone will freely rise through the body of heavy solvent and enter into the next higher zone.

The higher settling zone

The velocity in this settling zone is very low, and though the temperature may be high, a portion of the entrained solvent is permitted to settle from the rising solution and return to the next lower zone.

The precipitating zone

Deliberate cooling of the solution rising to this zone, coupled with low velocity in the relatively large body of solution, precipitates excess solvent, including entrained solvent particles. The precipitated solvent entrains in solution within itself the semi-naphthenic components residually left in the paraffinic solution, and this material is returned to the lower zones, instead of passing out with the paraffinic solution.

The products

Approximately all of the desired paraffinic components are carefully separated from the other components and discharged from the top of the cool precipitating zone, free of excess solvent and likewise free of contaminating degraded particles. A predetermined refined paraffinic solution is thus recovered from the system, and the relatively small percentage of solvent can be readily distilled from the paraffinic oil.

The extract discharged from the bottom of the column is approximately saturated with the most degraded components of the original oil. This deliberate saturation of the outgoing naphthenic solution with the most degraded components prevents escape of the more valuable paraffinic particles, and insures an ultimate recovery of practically all of the predetermined paraffinic material.

Aside from the special final operations at opposite ends of the system, it will be observed that the numerous varying intermediate conditions are quite different from the rather haphazard conventional ideas of merely mixing and settling successive solutions. In any extracting process of this kind, the composition is undergoing constant changes, beginning with the initial solution of raw oil and solvent, and very gradually progressing through numerous stages which ultimately provide a degraded solution and a radically different refined solution. The numerous different intermediate conditions are deliberately established to produce a most effective treatment in the combination of zones, and also at the successive stages in each zone.

Furthermore, all of the numerous special results can be very conveniently accomplished, and accurately controlled, in a simple counterflow system, lacking the various mechanical appliances, and elaborate apparatus ordinarily employed to provide a few of the desired special conditions.

As a specific example, we will refer to results obtained while operating under temperature conditions approximately as shown in Fig. 7 of the drawings. The original oil was a petroleum lubricating stock having an A. P. I. gravity of 23.9 and consisting of a blend of residue and distillate, known as bright stock. Dichlorethyl ether was employed as the selective solvent, using about three parts solvent to one part of the original oil. The resultant degraded naphthenic solution

contained 26.6% of the original oil stock, but this degraded solution as a whole consisted of 9.1% oil and 90.9% solvent. The paraffinic oil solution contained 73.4% of the original oil stock, and this solution as a whole consisted of 85.4% oil and 14.6% solvent. The recovered paraffinic oil had an A. P. I. gravity of 27.8 and a viscosity index of 98.8.

In another specific example, the original oil stock was a waxy lubricating oil distillate having an A. P. I. gravity of 23.9 and a viscosity index of 62.4. Dichlorethyl ether was employed as the selective solvent, using about 1 1/4 parts solvent to 1 part of the original oil stock. The resultant degraded naphthenic solution contained 33.8% of the original stock, but this degraded solution as a whole consisted of 18.3% oil and 81.7% solvent. The paraffinic oil solution contained 66.2% of the original stock, and this solution as a whole consisted of 78% oil and 22% solvent. The recovered paraffinic oil had an A. P. I. gravity of 30.6 and a viscosity index of 118.

The system can be very easily regulated to economically produce the very highest grade of raffinate and the lowest grade of extract, or any desired intermediate grades can be obtained with a corresponding degree of economy. In other words, a system of this kind is quite flexible and the several conditions can be easily varied to obtain the products most desirable under varying market conditions. Any suitable selective solvent may be used to extract lubricating oil stocks as well as numerous other kinds of oils, and any desired temperatures may be employed. Therefore, it is to be understood that the invention is not limited to the specific examples herein set forth, nor to any of the specific combinations of conditions, except as specified in the claims.

After the predetermined operating conditions have been established, the system can be operated continuously with very little attention upon the part of the operator, aside from routine observations.

To compensate for accidental or incidental variations which may occur from time to time, or to avoid unnecessary immediate attention to such variations, we have shown how an abnormal condition at one point in the system may be employed in regulating the flow through the system.

As an illustration of one form of this feature, attention is directed to the float 16 shown in Figures 1, 2 and 5. This float is secured to a pivot rod 17 extending through the column and provided with an external arm 18 connected to a valve 19. Air under pressure is transmitted to said valve 19 from an air supply pipe 20, and such air pressure may be transmitted through the valve 19 to a pipe 21 leading to a pneumatic valve 22 in the discharge conductor 4 leading from the bottom of the extracting column. These valves may be constructed in a conventional manner to permit adjustment of the discharge valve 22 in response to movements of the valve 19. In other words, the discharge of naphthenic extract from the bottom of the column may be varied in response to movements of the float 16.

To fully comprehend the results accomplished by such regulation, one should observe certain conditions existing in the portions of the column shown by Fig. 5.

This view illustrates several conditions at the upper portion of the extracting column, including the cooled precipitating zone, the warm settling zone, the warm solvent zone, and the top

of the scrubbing zone. Drastic cooling in the precipitating zone causes return of excess heavy solvent, etc., thereby providing a relatively light body of raffinate which passes out through the discharge conductor 5. All of the incoming heavy solvent may be admitted through the conductor 2 leading to the upper portion of the scrubbing zone. A body of this fresh solvent may be permitted to accumulate in the solvent zone, as shown in Fig. 5, thereby providing a relatively heavy body of liquid below the light paraffinic oil solutions in the higher zones. The heavy solvent body should not be permitted to rise through, or into, the precipitating zone, one of the objects being to exclude excess solvent from the outgoing raffinate.

In actual practice, there is a line of demarcation, or interface, between the body of heavy solvent and the next higher body of paraffinic solution.

To positively exclude the heavy body of solvent from the precipitating zone, and to maintain said interface at a desired elevation below the cooled precipitating zone and above the hot scrubbing zone, the float rises and falls in response to variations in the level of the interface. This float movement regulates the discharge of naphthenic solution (extract) from the lower portion of the column.

The incoming stream of fresh solvent and fresh oil, and also the heating and cooling, may be regulated as desired to produce the highest efficiency at each stage of the several zones. Thereafter, accidental or incidental variations will be compensated for by the float-controlled valve which regulates the discharge of the extract in accordance with conditions existing in other parts of the system, thereby maintaining the desired conditions at opposite ends of the system, regardless of such accidental or incidental variations.

For example, if the discharge of degraded extract is not sufficiently rapid, an excess of liquid will accumulate in the column, thereby increasing the elevation of the interface at the top of heavy solvent zone. The float will then rise to increase the discharge of degraded extract. Or, if the discharge of said extract is too rapid, the float will fall and thus decrease said discharge. On the other hand, if the discharge of light raffinate from the top of the column is too rapid, the body of solvent in the solvent zone will rise toward the top of the column, thereby moving the float to increase the discharge of extract at the bottom, which will relieve the excess, and prevent accidental discharge of fresh solvent in the outgoing refined raffinate.

Similar results can be accomplished by regulating the discharge of raffinate, or by varying the admission of fresh oil or fresh solvent. However, the foregoing illustrates one form of this feature, which prevents any very serious disturbance due to abnormal conditions which are likely to arise in any extracting system.

In the zones shown by Fig. 5, the liquid in the solvent zone may be almost entirely pure solvent, derived partly from the incoming fresh solvent stream, and partly from the higher zones. The scrubbed paraffinic solution leaves the top of the scrubbing zone by flowing along the bottom face of the baffle 6 shown in Fig. 5. This light solution rises from the periphery of said baffle in the form of light globules which pass through the body of heavy solvent as indicated in Fig. 5, and enter into the body of light paraffinic solution

in the settling zone. It will be observed that the light globules of paraffinic solution, rising through the solvent zone, contain the most insoluble portions of the original oil, so this material is not dissolved by the large body of solvent in said solvent zone. However, the rising globules will carry entrained solvent into the next higher settling zone, where the low velocity permits free settling of heavy solvent particles, which return to the solvent zone. A more drastic separation occurs in the higher precipitating zone where the deliberate cooling releases a substantial portion of additional solvent, which also returns to the solvent zone with residual semi-naphthenic components. Such residual components are thus returned for further treatment, instead of being permitted to escape with the outgoing paraffinic solution.

We claim:

- 20 1. In the art of using selective solvents to separate constituents of mineral oils, the method which comprises maintaining in a continuous counterflow system a series of zones including a precipitating zone, a scrubbing zone, a refluxing zone, and a saturating zone, transmitting the selective solvent into said scrubbing zone, introducing the mineral oil into said saturating zone, discharging the approximately saturated extract solution from said saturating zone, discharging the raffinate from said precipitating zone, dividing the intermediate solutions into numerous counterflowing layers contacting with each other in the refluxing and scrubbing zones and causing the layers to flow in intersecting paths, 30 maintaining the saturating zone at a relatively low temperature to permit free saturation of the outgoing solvent with the most degraded components of the oil, maintaining the contacting counterflowing streams in said refluxing zone at higher temperatures which increase in the streams passing from the saturating zone to the scrubbing zone and correspondingly decrease in the streams flowing toward said saturating zone, maintaining the counterflowing streams in the 40 scrubbing zone under prolonged high temperature conditions to provide time for the heated solvent to blend with the oil and dissolve intermediate components, transferring the raffinate stream from the top of said scrubbing zone to said precipitating zone, and maintaining said precipitating zone at a temperature substantially lower than the temperature of said scrubbing zone so as to separate entrained solvent and residual compounds from the outgoing raffinate stream.

- 55 2. In the art of using selective solvents to separate constituents of mineral oils, the method which comprises maintaining in a counterflow system a series of zones including a precipitating zone, a scrubbing zone below said precipitating zone, a refluxing zone below said scrubbing zone, and a saturating zone below said refluxing zone, continuously transmitting the selective solvent into said scrubbing zone, continuously transmitting the mineral oil into a lower zone, dividing the resultant solutions into counterflowing streams contacting with each other in said scrubbing zone and refluxing zone, discharging the lightest solution from said precipitating zone, while discharging the heaviest solution from a zone below said refluxing zone, maintaining a relatively high and approximately uniform temperature in said scrubbing zone while causing the counterflowing streams therein to flow in intersecting paths, deliberately cooling said pre-

cipitating zone to return a portion of the solvent with residual oil components to said scrubbing zone, progressively decreasing the temperature of the descending streams in said refluxing zone while increasing the temperature of the rising streams in the same zone and causing the different streams to flow in intersecting paths in said refluxing zone, transmitting the heaviest portions of the descending streams into said saturating zone, and maintaining a relatively low temperature in said saturating zone to produce a solution approximately saturated with the most naphthenic components of the oil.

3. In the art of using selective solvents to separate constituents of mineral oils, the counterflow method which comprises maintaining in a continuous counterflow system a series of zones including a cool precipitating zone, a hot settling zone below said precipitating zone, a hot solvent zone below said settling zone, and cooler more naphthenic zones below said hot solvent zone, introducing the selective solvent into said solvent zone, introducing the mineral oil into one of said cooler zones, discharging the raffinate from said precipitating zone, discharging the extract from the opposite end of the system, dividing the intermediate solutions into numerous counterflowing streams contacting with each other, and causing said streams to flow in intersecting paths, transmitting the rising stream through the hot solvent zone and thence through said hot settling zone, maintaining a relatively low velocity in said hot settling zone to freely separate entrained heavy solvent from the rising stream, transferring the rising stream from the top of said hot settling zone to the cool precipitating zone, and maintaining said cool precipitating zone at temperatures substantially below the temperatures of the adjacent lower zones, so as to separate excess solvent and residual heavy compounds from the outgoing raffinate stream.

4. In the art of using selective solvents to separate constituents of mineral oils, the counterflow method which comprises maintaining in a continuous counterflow system a series of zones including a cool precipitating zone, a hot solvent zone below said cool precipitating zone, a hot scrubbing zone below said solvent zone, a refluxing zone below said scrubbing zone, a saturating zone below said refluxing zone, and a saturated releasing zone below said saturating zone, introducing the selective solvent into said solvent zone, introducing the mineral oil at a point adjacent to the bottom of said saturating zone, discharging the extract from the saturated releasing zone, discharging the raffinate from said precipitating zone, dividing the intermediate solutions into numerous counterflowing streams contacting with each other in the saturating zone, refluxing zone and scrubbing zone, and causing said streams to flow in intersecting paths in each of the last mentioned zones, maintain-

ing the saturating zone at a relatively low temperature and maintaining a relatively low velocity in said saturating zone to permit free saturation of the descending solvent with the most degraded components of the oil, maintaining a low temperature and a still lower velocity in said saturated releasing zone to release entrained particles of paraffinic compounds from the outgoing saturated solution, maintaining the contacting counterflowing streams in said refluxing zone at substantially higher temperatures which increase in the streams rising toward said scrubbing zone and correspondingly decrease in the streams descending toward said saturating zone, at the same time increasing the velocity of the streams progressing toward said scrubbing zone, while decreasing the velocity of the companion streams flowing toward said saturating zone, maintaining the contacting counterflowing streams in said scrubbing zone under prolonged high temperature conditions to provide time for the heated solvent to blend with the oil and dissolve intermediate components which enter into the descending streams, and progressively increasing the velocity of the rising streams as they advance toward the top of said hot scrubbing zone so as to increase the scrubbing action, transferring the rising stream from said hot solvent zone to the cool precipitating zone, and maintaining said cool precipitating zone at temperatures substantially below the temperatures of the adjacent lower zones, so as to separate excess solvent and residual heavy compounds from the outgoing raffinate stream.

5. In the art of using selective solvents to separate paraffinic and naphthenic constituents of mineral oils, the counterflow method which comprises maintaining in a continuous counterflow system a series of zones including a cool precipitating zone, a hot solvent zone below said precipitating zone, and cooler more naphthenic zones below said hot solvent zone, introducing the selective solvent into said solvent zone, introducing the mineral oil into one of said cooler zones, discharging the paraffinic raffinate from said precipitating zone, discharging the naphthenic extract from the opposite end of the system, dividing the intermediate solutions into numerous counterflowing streams contacting with each other, and causing said streams to flow in intersecting paths, transmitting the rising stream through the hot solvent zone and to said cool precipitating zone, maintaining said cool precipitating zone at temperatures substantially below the temperatures of said solvent zone, so as to separate excess solvent and residual heavy compounds from the outgoing raffinate stream, maintaining a substantial body of solvent in said solvent zone, and regulating the discharge of said naphthenic extract in accordance with variations in the level of said body of solvent.
